UNITED STATES PATENT OFFICE.

JEROME B. SECOR, OF CHICAGO, ILLINOIS.

DESIGN FOR SEWING-MACHINE LEGS.

Specification forming part of Design No. 5,155, dated August 1, 1871.

To all whom it may concern:

Be it known that I, JEROME B. SECOR, of Chicago, in the county of Cook and State of Illinois, have invented and produced a new and original Design for Sewing-Machine Legs or Supports, of which the following is a specification:

The nature of my design is fully represented in the accompanying drawing, to which reference is made.

I claim as my invention—
The design for sewing-machine legs or supports, as shown.

JEROME B. SECOR.
